CUSHIONED SHOE HEEL

Filed April 11, 1944

UNITED STATES PATENT OFFICE

2,370,889

CUSHIONED SHOE HEEL

William Elbert Stout, Baltimore, Md.

Application April 11, 1944, Serial No. 530,495

12 Claims. (Cl. 36—36)

This invention relates to cushioned heels for shoes, and one of its objects is to provide a composite rubber heel which will have maximum capacity for wear and which, at the same time, will have sufficient resistance to compression and yet give a soft, elastic or velvety cushioning action to absorb shocks and jars to a degree not possible with rubber or other cushioned heels of ordinary construction.

Another object of the invention is to provide a cushioned heel formed of sections of rubber of different degrees of resiliency which not only give greater durability than an ordinary rubber heel, but which at the same time will give a much greater cushioning effect.

Still another object of the invention is to provide a cushioned heel comprising a top lift formed of rubber of certain degrees of hardness and resiliency, such as used in ordinary rubber shoe heels, and a bottom lift formed of a softer and more highly resilient rubber, such as sponge rubber, said lifts being united to form a unitary heel in such manner as to prevent casual separation thereof and so as to secure flexing and cushioning actions of novel character and to degrees much beyond such qualities possessed by ordinary rubber heels.

Still another object of the invention is to provide a cushioned heel which is of detachable type, allowing a worn out heel to be readily removed and a new one applied in its place, and which when applied will not mar or detract from the appearance of the shoe and will be firmly secured against possibility of casual disconnection or of becoming loose from the shoe.

Still another object of the invention is to provide a construction adapting the heel to be firmly glued as well as mechanically fastened to the shoe and the lifts to be similarly united so as to secure stability of construction as well as to seal all joints against the entrance of moisture and other foreign substances.

With these and other objects in view, the invention consists of the novel features of construction, combination and arrangement of parts hereinafter fully described and claimed, and as shown in the accompanying drawing, in which:

Figure 1 is a side elevation of the rear portion of a shoe, showing my improved cushioned heel applied thereto.

Figure 2 is a bottom plan view of the same.

Figure 3 is a longitudinal section on the line 3—3 of Figure 6 through the heel portion of the shoe sole and the cushioned heel.

Figure 4 is a detail section on the line 4—4 of Figure 3.

Figure 5 is a front elevation, partly in section, of the cushioned heel removed from the shoe.

Figure 6 is a top plan view thereof.

Figures 7 and 8 are enlarged detail sections on the lines 7—7 and 8—8 of Figure 6.

Figure 9 is a cross section through the heel portion of the shoe sole and the cushioned heel applied thereto as shown in Figure 6.

Figure 10 is a perspective view of the reinforcing and attaching plate.

Figures 11 and 12 are diagrammatic views, illustrating a fitting and joint sealing effect obtained by a feature of construction.

Referring now more particularly to the drawing, 1 designates the heel portion and 2 the shank portion of the sole of a shoe of any ordinary type or construction, and 3 designates as a whole my improved cushioned heel for attachment to the heel portion 1 of the shoe sole. The heel portion 1, as shown, may have the usual general outline shape of a horseshoe and its outer surface 4 may be of usual form, that is, slightly convex both longitudinally and transversely.

The heel 3, which is of the same general outline or peripheral shape as the heel portion 1, comprises an outer or tread section 5 and an inner or cushioning pad section 6. These sections may be of the same or different relative thicknesses or depths, according to the degree of cushioning action desired, and when applied to the shoe said sections are peripherally aligned and conform in external contour to each other and to the periphery of the heel portion 1. The section 6, however, is initially of an external contour slightly different from that of the section 5 and is compressed into a shape corresponding thereto when applied to the shoe, as and for the purpose hereinafter described, and it is to be understood that these sections may cooperatively vary in external form as may be desired or required in the production of different types or shapes of heels. The heel shown for purpose of exemplification is one designed for use on a man's walking shoe of conventional type, and its shape may be varied in adapting it for application to women's shoes or shoes designed to cure or correct foot defects or to serve other special purposes. I do not limit the invention in this respect or in any other respect, except as and when specifically defined in the appended claims.

The tread section 5 is formed of comparatively hard rubber having a certain degree of resiliency

and may conform in this respect to an ordinary rubber heel formed of rubber of such consistency as to be wear resisting and of sufficient resilience to give a certain degree of cushioning action and to allow particular bending or flexing movements of the sole as a whole. The section 6, however, is formed of a relatively softer rubber of higher resiliency, such as sponge rubber, which yieldingly backs the section 4 and provides a cushion which absorbs the shocks and jars to which the heel is subjected in service and allows desired bending or flexing movements of the heel as a whole to be obtained. In practice, the tread face of the section 5 may be formed or provided with any kind or shape of gripping means for gripping engagement with the ground to effectually prevent slippage.

The opposed contacting faces 7 and 8 of the sections 5 and 6, to wit, the inner face of the section 5 and the outer face of the section 6, may be plain surfaced or otherwise formed to lie in close contact. The surface 7 of the section 5 is, however, preferably slightly concaved to form a seat for the face 8 of the section 6 which tends to hold the sections 5 and 6 from relative lateral and longitudinal shifting or creeping movements. To positively hold the sections from such movements and to permit of the use of flexible holding connections between the same, a coating or layer of waterproof glue or cement may be employed to bind them together and to close the joints at the margins thereof against the access of moisture and other foreign substances.

The section 6 is provided with a concaved inner face 10 which fits against the convex surface 4 of the heel portion 1 of the shoe sole. Disposed in the cavity or recess formed by this face 10 is a reinforcing and attaching plate 11 formed of metal, plastic material or other suitable material. This plate is generally shaped to conform externally to the external shape of the section 6, but is of less superficial dimensions, longitudinally and transversely, than the face 10, and has its front, rear and side edges lying inwardly of and spaced from the corresponding edges of the section 6, leaving exposed a marginal portion 12 of the face 10 bounding and extending beyond the edges of the plate.

The plate 11 is provided at its front and rear with centrally disposed, longitudinally extending tongues 13 and 14. The tongue 13 is of some length and projects beyond the breast of the heel and is provided with an opening 15, while the tongue 14 is comparatively short and laps only to a certain extent over the margin 12 of the face 10. The tongue 13 is employed as one of the elements for attaching the heel at the front to the sole of the shoe, and the tongue 14 serves as a plate extension to reinforce the plate 11 and section 6 in the region of and to compensate for the removal of metal from the plate to form a keeper opening 16 and locking tongue 17 constituting part of means for attaching the heel at the rear to the sole of the shoe. The tongue 17 is partially separated at its sides from the plate by slits 17' to allow the tongue to have a certain degree of spring action or resiliency. The free end of the tongue 17 is bent or coiled to form a keeper loop or eye 18 lying beneath the plate and above alined openings 19 in the heel sections 5 and 6, and at its front corners the plate is provided with downward portions which are bent or coiled to form similar keeper loops or eyes 20 and 21 lying above openings 22 and 23 in the heel sections 5 and 6.

Means are provided for cooperation with the plate 11 to yieldingly fasten the sections 5 and 6 together to form a unitary heel and to firmly and securely, but detachably, fasten the unitary composite heel to the shoe. The means for yieldingly fastening the sections 5 and 6 together comprises looped thong strips 24, 25 and 26 which are passed at their bight portions through links 27 engaged with the keeper loops or eyes and have their limbs depending therefrom and extending in parallel relation into and through the openings 19, 22 and 23 to the wear surface of the section 5. The links of each of these looped thongs snugly fit the opening in which they are arranged and they are secured to the heel section 5 by fastening pins 28 firmly held in said heel section. In applying the thongs to the heel the thongs are drawn tightly and fastened by the pins to hold the sections 5 and 6 firmly bound together and they are cut off flush with the wear face of the section 5 so that the end edges thereof will be exposed to form auxiliary antislipping projections. Preferably the thongs are made of rawhide or some other suitable strong and durable material adapted to wear away with the wear surface of the section and to resist unduly rapid wear thereof. The thongs, while securely holding the sections 5 and 6 united, provide flexible ties adapted to bend or flex in the openings 30 and thus allow compression and expansion of the section 6 for maximum cushioning actions, while at the same time allowing portions of the heel to independently bend or flex and to bend or flex to different degrees and to thereby have flexing and cushioning movements not possible with other cushioned heels. In some cases flexible steel strips may be used in place of the rawhide thongs.

The means employed in connection with the plate 11 for fastening the heel to the shoe comprises a threaded stud or bolt 29 fixed to and projecting from the shank 2 and a staple or like keeper member 30 fixed to and projecting from the sole portion 1. The stud 29 is adapted to be engaged with the opening 15 in the tongue 13 and to receive a nut or like fastener to force the tongue 13 against the shank 2 and hold the forward portion of the heel fastened thereto. The keeper 30 is adapted to receive the tongue 17 to hold the heel with a tight compression fit against the surface 4 of the heel portion of the shoe sole.

The concavity 10 in the section 6 preferably extends on an arc of greater degree than the surface 4 of the sole portion of the shoe and the marginal surface 12 and adjacent portions of the outer surfaces or sides of the section 6 converge and extend upwardly in the form of triangular peaks, making the width of the top of the section 6 somewhat less than the width of the surface 4. By this construction these peaked portions are adapted, when the heel is applied to the shoe, to be flattened out so as to make the surface 10 conform to and fit closely against the surface 4 so as to place the applied heel as a whole somewhat under tension and obtain binding engagement to make the connection sure against any possibility of disconnection from the shoe and proof against entrance of moisture or other foreign substance between the shoe and heel. Fig. 11 illustrates diagrammatically the relative shapes of the surfaces 4 and 10 prior to the application of the heel, and Fig. 12 illustrates the form the surface 10 takes when the heel is fastened by the fastening connections under stress to the sur-

face 4. The marginal portion 12 of the surface 10 provides a binding and sealing area about the plate 11 which may be glued or cemented, as shown at 12', to the surface 4 to form a marginal fastening and joint sealing connection, but, if desired, the whole of the surface 10, including the plate 11, may be glued to the surface 4.

The parts of the heel when assembled form a unitary heel, and such heels in proper sizes may be furnished to shoe manufacturers and repairers for application to shoes provided with the fastening elements 29 and 30. In applying a heel to shoes unprovided with the fastening elements 29 and 30, these elements may be readily affixed to the shoe by a repairman. It is also possible for a shoe wearer having a certain amount of mechanical ability to apply the elements to his shoes, and it is an easy matter for any person whose shoes are furnished with the elements 29 and 30 to remove a worn out heel and apply a new heel in its place without the use of any special tool or tools.

In applying a heel to a shoe provided with the elements 29 and 30 the heel is brought to a position beneath the portion 4 so that the element 30 will align with and may enter the opening 16 in advance of the tongue 11. The heel is then pressed against the shoe to cause the portions 12 to be flattened out and the keeper element 30 to depress the portion of the heel section 6 adjacent to the tongue and to come into the plane of the tongue, whereupon the heel is slid forwardly on the surface 4 to bring the heel into proper position and to cause the tongue to enter the keeper element 30 and to interlock therewith. This forward movement of the heel is at a slight angle to the plane of the surface 4, during which the tongue 13 rides on the stud 29 until the stud registers with the opening 15 and engages therewith. The nut 31 is then screwed on the stud so as to force the tongue 13 upward and firmly clamp it against the shoe shank. In these applying actions the tongue 17 acts as a cam or wedge in connection with the nut 31 as a force feed element to force or jam the heel against the surface 4 to secure the sealing fit shown in Fig. 12 and to flatten out and clamp the surfaces 12 under tension against the surface 4, whereby a mechanically secure sealing fit of the heel against the sole portion 4 is secured. To remove a worn out heel for substitution of a new heel, it is simply necessary to first remove the nut 31 and then force the tongue 13 out of engagement with the stud 29, after which the heel may be detached by sliding it rearwardly to force the tongue 17 out of engagement with the keeper element 30.

The advantages of my novel and improved construction of heel are manifold. The section 5 gives long wear and stability to the heel with a desirable degree of flexibility for certain cushioning elements. The section 6 allows a much greater cushioning movement to be obtained than is possible with other cushioned heels. This cushioning movement is mainly vertical or perpendicular to the plane of the heel to absorb shocks and jars, but angular flexing movements of the heel and portions thereof are also permitted because of the resiliency of the section 6 and flexibility of the section 5. These angular movements relieve the foot from stresses and strains liable to be caused in walking over rough surfaces or stepping from one elevation to another.

The function of the plate 11, in addition to serving as a fastening medium, is to reinforce the section 6 throughout sufficient of its area to hold

it from torsional and other strains liable to distort it. Its construction adapted it to provide a strong and durable fastening medium while exposing the portion 12 to adapt the heel to be applied with the desirable binding and sealing effect hereinbefore described. By the use of the flexible thongs or tie connections 24, 25 and 26 the necessity of using rigid types of fastenings is avoided and greater flexibility of the heel and a higher degree of cushioning action obtained.

My improved heel, while providing a heel of greater cushioning efficiency than ordinary heels, is also adapted for use on ordinary shoes to correct certain foot defects and on special shoes made for the purpose, for the reasons stated, and since the relative thicknesses of the sections 5 and 6 may be varied to meet required conditions.

Openings 31 may be provided in the marginal portion 12 of the heel section 6 to allow this part to have greater flexibility and to more readily conform to the sole part 2.

While the construction of the heel as herein disclosed as an exemplary one is preferred, it is to be understood that I do not limit myself thereto, as changes in the form, construction and arrangement of parts, and character of materials employed, may vary within the scope of the appended claims, without departing from the spirit or sacrificing any of the advantages of the invention.

Having thus described my invention, I claim:

1. A cushioned heel for shoes including an outer section of comparatively hard rubber, an inner section of comparatively soft cushioning rubber, and means extending between and flexibly connecting said sections.

2. A cushioned heel for shoes including an outer section of comparatively hard rubber, an inner section of comparatively soft cushioning rubber, and tie elements of flexible material extending between and flexibly connecting said sections.

3. A cushioned heel for shoes including an outer section of comparatively hard rubber, an inner section of comparatively soft cushioning rubber, a reinforcing and stiffening member resting on the inner surface of the inner section, and tie elements extending between the sections and attached to the outer section and said member and flexibly connecting the sections.

4. A cushioned heel for shoes including an outer section of comparatively hard rubber, an inner section of comparatively soft cushioning rubber, a reinforcing and stiffening plate resting on the inner surface of said member and marginally spaced from the marginal surfaces thereof, and tie elements extending between the sections and attached to the plate and outer section and flexibly connecting said sections.

5. A cushioned heel for shoes including an outer section of comparatively hard rubber, an inner section of comparatively soft cushioning rubber, said inner section having a longitudinally and transversely concaved upper face, a reinforcing and stiffening plate disposed in the cavity of said face and marginally spaced from the margins of the inner section, and flexible tie elements extending between the sections and attached to the plate and outer section.

6. A cushioned heel for shoes including an outer section of comparatively hard rubber, an inner section of comparatively soft cushioning rubber, said inner section having a longitudinally and transversely concaved upper face, a reinforcing and stiffening plate disposed in the cavity of said face and marginally spaced from the mar-

gins of the inner section, and a series of tie elements of flexible material attached at their inner ends to the rear portion and front corner portions of the plate and extending therefrom through the inner section into and attached at their outer ends to the outer section.

7. In a cushioned heel for shoes, and in combination with the sole of a shoe having a heel portion, a cushioned heel adapted to be attached to the heel portion of the sole and comprising an outer section of comparatively hard rubber, an inner section of comparatively soft cushioning rubber having a surface to bear on the heel portion of the shoe sole, fastening elements on the shoe sole, fastening means including a stiffening member resting on said surface of the inner section and provided with means to engage the fastening means on the shoe sole, and connecting elements extending between the heel sections and attached to the plate and outer heel section and flexibly connecting the heel sections.

8. In a cushioned heel for shoes, and in combination with a shoe sole having a heel portion, a cushioned heel adapted to be attached to the heel portion of the sole comprising an outer section of comparatively hard rubber, an inner section of comparatively soft cushioning rubber having a surface to bear on the heel portion of the shoe sole, fastening elements on the shoe sole, fastening means including a stiffening member resting on said surface of the inner section and provided with means to engage the fastening means on the shoe sole, and connecting elements extending between the heel sections and attached to the said member and to the outer heel section and flexibly connecting the heel sections together.

9. In a cushioned heel for shoes, and in combination with a shoe sole having a heel portion, a cushioned heel adapted to be attached to the heel portion of the sole comprising an outer section of comparatively hard rubber, an inner section of comparatively soft cushioning rubber having a surface to bear on the heel portion of the shoe sole, fastening elements on the shoe sole, a reinforcing and stiffening plate resting on said surface of the inner section and provided with means to engage the fastening means on the shoe sole, and connecting elements extending between the heel sections and attached to the plate and to the outer heel section and flexibly connecting the heel sections together.

10. In a cushioned heel for shoes, and in com-

bination with a shoe sole having a heel surface of convex form, a cushioned heel adapted to be attached to the heel surface of the sole comprising an outer section of comparatively hard rubber, an inner section of comparatively soft cushioning rubber having a concaved surface to bear on the heel surface of the shoe sole and extending on an arc of greater radial than the convex surface, fastening elements on the shoe sole, fast-

10 tening means including a stiffening member resting on said surface of the inner section and provided with means to engage the fastening means on the shoe sole and cooperating therewith to force the heel against the heel surface of the sole to flatten out the concaved surface of the inner heel section to conform to the heel surface of the sole, and connecting elements extending between the heel sections and attached to the plate and to the outer heel section and flexibly connecting the heel sections together.

11. In a cushioned heel for shoes, and in combination with a shoe sole having a heel portion, a cushioned heel adapted to be attached to the heel portion of the sole comprising an outer section of comparatively hard rubber, an inner section of comparatively soft cushioning rubber having a surface to bear on the heel portion of the shoe sole, fastening elements on the shoe sole, a reinforcing and stiffening plate resting on said surface of the inner section and provided with fastening elements to engage the fastening elements on the shoe sole, and connecting elements extending between the heel sections and attached to the plate and to the outer heel section and flexibly connecting the heel sections together.

12. In a cushioned heel for shoes, and in combination with a shoe sole having a heel portion, a cushioned heel adapted to be attached to the heel portion of the sole comprising an outer section of comparatively hard rubber, an inner section of comparatively soft cushioning rubber having a surface to bear on the heel portion of the shoe sole, fastening elements on the shoe sole, a reinforcing and stiffening plate resting on said surface of the inner section and provided with fastening elements to engage the fastening elements on the shoe sole, and flexible connecting elements extending between the heel sections and flexibly attached at their inner ends to the plate and at their outer ends to the outer heel section.

WILLIAM ELBERT STOUT.
